UNITED STATES PATENT OFFICE.

HERBERT L. OSBORN, OF SEATTLE, WASHINGTON.

COMBINATION-TRUNK.

1,312,044.

Specification of Letters Patent.

Patented Aug. 5, 1919.

Application filed November 27, 1917. Serial No. 204,222.

To all whom it may concern:

Be it known that I, HERBERT L. OSBORN, a citizen of the United States of America, residing at Seattle, in the county of King and State of Washington, have invented certain new and useful Improvements in Combination-Trunks, of which the following is a specification, reference being had therein to the accompanying drawing.

10 This invention relates to a combination trunk and has for its object the production of a simple and efficient trunk which may be conveniently carried upon an automobile or other vehicle, and which may be readily converted into a table.

Another object of this invention is the production of a simple and efficient hinge structure, used in connection with the folding sides of the trunk, whereby the folding sides 20 may be thoroughly braced when the same are in an extended relation.

With these and other objects in view this invention consists of certain novel combinations and arrangements of parts as will be 25 hereinafter fully described and claimed.

In the drawings:—

Figure 1 is a front elevation of the trunk.

Fig. 2 is a rear elevation of the trunk.

Fig. 3 is an end elevation of the trunk.

30 Fig. 4 is a vertical transverse section through the trunk.

Fig. 5 is an end elevation of the trunk, in an extended position, when the same is used as a table.

35 Fig. 6 is a transverse section through the trunk in its extended position, while the same is being used as a table.

Fig. 7 is a bottom plan view of the trunk showing the supporting legs in a folded position.

40 Fig. 8 is a section taken on the line 8—8 of Fig. 7.

Fig. 9 is a detail perspective of the latching means for holding the legs in a folded position.

45 Fig. 10 is a detail perspective of the body of the trunk, showing one corner thereof, and illustrating one of the folding leaves connected thereto.

50 Fig. 11 is a detail perspective of a portion of the primary and secondary leaf of the trunk, showing the bracing hinges in a folded position.

Fig. 12 is a detail perspective of the primary and secondary leaf, showing a por-

tion thereof in section, and a bracing hinge being shown in an extended position.

Fig. 13 is a vertical section through one of the bracing legs, showing the means of connecting the same to one of the outer leaves 60 of the table, which form a part of the trunk.

By referring to the drawings, it will be seen that 1 designates the body of the trunk, which comprises a front side 2, and a bottom 3, the corners thereof being braced by means of the metallic bracing strips 4. The bottom 3 is provided with a longitudinally extending rail 5 across the front thereof, and a primary leaf 6 is hingedly connected to this rail 5 by means of a hinge 7. A secondary leaf 8 is connected to the outer edge of the leaf 6 by means of the specially constructed hinges 9, which will be hereinafter fully described. The adjoining edges 10 of the primary and secondary leaves 6 and 8 70 are beveled, as indicated clearly in Fig. 4 to permit the primary and secondary leaves to be folded at right angles to each other. The intermediate leaf 11 is hingedly secured to its outer edge to the outer edge of the secondary leaf 9, and an outer leaf 12 is in turn hingedly secured to the edge of the intermediate leaf 11. The abutting edges of the leaves 11 and 12 are beveled as indicated by the numeral 13 in Fig. 4, in 80 order to permit the leaves to be folded at right angles to each other. The primary and secondary leaves 6 and 8 are reinforced at the edges thereof, by suitable reinforcing straps 14 and the intermediate and outer leaves 11 and 12 are provided with inwardly extending flanges 15 formed upon the sides of the leaves in order to overhang the body 1 of the trunk, when the device is in a folded position, as is clearly indicated in Fig. 4. 90

The flanges 15 are braced by means of the toggle links 16, at their junctions between the intermediate and outer leaves 11 and 12. This structure is clearly illustrated in Fig. 3 of the drawing. 100

A pair of supporting legs 17 are hingedly secured to the intermediate leaf 11, by means of the hinges 18, and these bracing legs 17 are provided with adjustable ends 19 carrying locking straps 20^a, which are adapted to hold the adjustable ends in a fixed position, in order to permit the legs to support the leaves in a proper extended position, should the table be set up upon an uneven surface. A pair of suitable legs 20 are carried by the 110

outer leaf 12, and are secured to the under face of the outer leaf 12, by means of suitable hinges 21. These legs 20 are adjusted in a manner similar to that described with 5 respect to the legs 17. These legs 17 and 20 are adapted to be swung at right angles to the leaves 11 and 12, in order to constitute an efficient support therefor. When the device is used as a trunk or packing case, these 10 legs 17 and 20 are adapted to be folded down upon the inner face of the leaves 11 and 12, as shown in Fig. 4 and to be held firmly in this folded position by means of the latching bar 22, which latching bar 22 is pivotally 15 connected to a wire frame 23 at one end, and has its opposite end fitting under a spring hook 24 of the frame 23. This frame 23 is provided with suitable looped-portions 25 for facilitating the attachment of the frame 20 23 to the under face of the leaves 11 and 12.

By carefully considering especially Figs. 11 and 12 it will be seen that a specially constructed hinge 9 is employed for constituting a brace for the primary and secondary leaves 6 and 8, while the same are in 25 an extended position.

This specially constructed hinge 9 comprises a pair of primary leaves 26, which are secured to the leaves 6 and 8 and are also 30 hinged together at their inner ends. A bracing leaf 27 is hinged along its longitudinal edge to each primary leaf 26 of the hinge, and the abutting ends of the bracing leaves 20 are hinged together. It 35 should be understood that the hinge may be folded flat upon the primary and secondary leaves 6 and 8 of the trunk, in order to permit these leaves 6 and 8 to extend at right angles to each other. However, when the 40 device is used as a table the bracing leaves 27 may be swung at right angles to the table leaves 6 and 8 as shown in detail at Fig. 12, and thereby constituting a sufficient brace and holding the primary and secondary 45 leaves 6 and 8 in parallel relation with respect to each other. By means of the specially constructed hinge 9, as above described a very efficient bracing means has been produced, as is clearly illustrated in Figs. 5 and 50 6 for holding the leaves of the trunk in an extended position for presenting a flat top, to be used as a table.

From the foregoing description, it will

be seen that a very simple and efficient foldable box or trunk has been produced, which 55 is especially adapted for use by tourists and the like, wherein the trunk may be used not only as a receptacle for storing, or conveying articles, but may also be readily converted into a table, when extended as above 60 described.

It should, of course, be understood, that suitable detail mechanical changes may be made in connection with the present device, without departing from the spirit of the invention. 65

What is claimed is:—

1. In a combination trunk of the class described, the combination with a body-structure having an open top, an open front, and a non-open back, of a plurality of leaves hingedly connected together and one hingedly secured to the upper portion of said back, said leaves adapted to be folded upon the body-structure to close said open 70 top and front to produce a complete box, part of said leaves resting under the other leaves when folded, all of the leaves adapted to be unfolded for producing a table, and legs for said leaves when in said table-forming position, substantially as shown 75 and described. 80

2. In a combination trunk of the class described, the combination with a body-structure having an open top, an open front, and a non-open back, of primary and secondary leaves hingedly connected together and an intermediate leaf and an outer leaf hingedly connected together, said intermediate leaf being hingedly connected to said secondary leaf, said primary leaf hingedly connected to the back of said body-structure, said leaves adapted to be folded upon the body-structure for closing the top and front 85 for producing a complete box or trunk, bracing means interposed between said outer and intermediate leaves for holding the same in a parallel position, and adjustable legs 90 hingedly secured to the inner face of said intermediate and outer leaves and capable of being swung at right angles thereto for 95 constituting a sufficient support therefor. 100

In testimony whereof I hereunto affix my signature.

HERBERT L. OSBORN.
